US0D1000957S

(12) **United States Design Patent** (10) **Patent No.:** **US D1,000,957 S**
(45) **Date of Patent:** **** Oct. 10, 2023**

(54) **PACKAGING BOX INSERT**

(71) Applicant: **Han Yong Cho**, Yongin-si (KR)

(72) Inventor: **Han Yong Cho**, Yongin-si (KR)

(73) Assignee: **Han Yong Cho**, Yongin-si (KR)

(**) Term: **15 Years**

(21) Appl. No.: **29/805,961**

(22) Filed: **Aug. 31, 2021**

(30) **Foreign Application Priority Data**

Aug. 6, 2021 (KR) 30-2021-0037404

(51) **LOC (14) Cl.** **09-07**

(52) **U.S. Cl.**

USPC **D9/456**

(58) **Field of Classification Search**

USPC D9/456, 433, 434, 455, 499, 414, 425,
D9/432, 439

CPC B65D 81/133; B65D 5/48028; B65D

(57) **CLAIM**

I claim the ornamental design for a packaging box insert, as
shown and described.

DESCRIPTION

FIG. 1 is a top perspective view of packaging box insert,
showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a bottom perspective view thereof.

1 Claim, 5 Drawing Sheets
